CLAIM

The ornamental design for a removable toilet seat cushion, as shown and described.

DESCRIPTION

FIG. 1 is a top perspective view of a removal toilet seat cushion, showing my new design;

FIG. 2 is a top plan view thereof;

FIG. 3 is a side view, the opposite side being a mirror image thereof;

FIG. 4 is a front view thereof;

FIG. 5 is a rear view thereof; and,

FIG. 6 is a top perspective view thereof, with a fringe material shown in broken lines.

The broken line showing is for illustrative purposes only and forms no part of the claimed design.
